UNITED STATES PATENT OFFICE.

COLLINS ARNOLD, OF ALBANY, NEW YORK.

MOVABLE STORAGE-POCKET.

SPECIFICATION forming part of Letters Patent No. 749,653, dated January 12, 1904.
Application filed January 16, 1903. Serial No. 139,317. (No model.)

To all whom it may concern:

Be it known that I, COLLINS ARNOLD, a citizen of the United States, residing at Albany, county of Albany, and State of New York, have invented certain new and useful Improvements in Movable Storage-Pockets, of which the following is a specification.

The invention relates to such improvements; and it consists of the novel construction and combination of parts hereinafter described and subsequently claimed.

Reference may be had to the accompanying drawings and the reference characters marked thereon, which form a part of this specification.

Similar characters refer to similar parts in the several figures.

This invention is well adapted for use in libraries and stores where the upper shelves or pockets used to support books, dry goods, or other commodities are beyond the reach of the attendant.

The object of the invention is to provide means for moving the upper shelves or pockets up and down, so that when moved to a lower level their contents are easily accessible and when moved to a high level their contents are stored where the room occupied is less valuable on account of its comparative inaccessibility.

The invention consists in dividing the shelves or other supports in the upper part of a storage-case into movable sections or pockets, providing a counterbalance common to a plurality of pockets and mechanism for moving the storage-pockets up and down one at a time and making the connections between the pocket moved and the counterbalance active while the connections between the counterbalance and the other pockets remain inactive, and means for regulating and controlling the movements of the various parts, as herein-after more fully described and subsequently claimed.

Referring to the drawings, Figure 1 is a front elevation of an upper portion of a storage-case provided with my improved apparatus with the front of the inclosure for the mechanism removed, showing the cross-partitions in section and showing one of the stor-

age-pockets suspended at a level below its normal position. Fig. 2 is a vertical cross-section taken on the broken line 22 in Fig. 1, showing the front of the mechanism inclosure in cross-section. Fig. 3 is a rear elevation of the parts shown in Fig. 1 and showing a part of the counterbalance. Fig. 4 is a vertical section similar to that shown in Fig. 2, showing one of the pocket-supporting drums in side elevation. Fig. 5 is a top plan view of the part shown in Fig. 4. Fig. 6 is a section similar to that shown in Fig. 4, showing in side elevation the locking mechanism for locking the storage-pockets in a given position, the mechanism being shown in a locked position. Fig. 7 is a similar view of the parts shown in Fig. 6, showing the parts in an unlocked position. Fig. 8 is a vertical section taken on the broken line 88 in Fig. 3 looking in the direction of the arrow. Fig. 9 is a top plan view of the parts shown in Fig. 8. Fig. 10 is a central vertical section of the governor mechanism, taken on the broken line 1010 in Fig. 1. Fig. 11 is a vertical section taken on the broken line 1111 in Fig. 1 looking in the direction of the arrow.

The storage-case 1 (shown in part only in the drawings) may extend the whole length of one side of a room, being provided with shelving 2 for the reception of books or other commodities, the upper portion being divided into sections or storage-pockets, one of which, 3, is shown in full and in its normal upper position, and another, 4, shown in part and suspended at a lower level. The upper portion of the storage-case is divided into similar sections throughout its length. In the upper portion of the case-frame are provided suitable bearings for the rotary shaft 5, which may extend the entire length of the storage-case. Upon this shaft are loosely-mounted drums 6, preferably two for each storage-pocket, which drums are connected with the pocket by means of pocket-supporting cables 7, one end of each cable being secured to a toothed wheel 8, mounted upon shaft 9, supported in suitable bearings in the block 10, secured to the upper end of the pocket, the other end of the cable being secured to drum 6 and adapted to be wound thereon. The toothed wheel can be

rotated to wind the cable 7 upon shaft 9, thereby providing means for adjusting the effective length of the cable, the toothed wheel being held in the desired position by means of the 5 spring-stop 11, secured to the upper end of the pocket, as shown. There are also mounted upon the shaft 5 two or more drums 12, fixed by set-screws 14 to rotate with the shaft. Cables 15 have one end secured to one of these 10 fixed drums and the other end secured at 16 to a portion of the case-frame, the cables passing under the counterbalancing-weight 20. The counterbalance is provided with grooves 21, adapted to receive the cables.

15 As a means for actively connecting the storage-pockets one at a time with the counterbalance through the drums, cables, and drum-supporting shaft I provide for each loose drum a series of clips 22 on the shaft. I have shown 20 in the drawings four clips. The outside clip 23 most remote from the drum is provided with a hub 24, which is fixed upon the shaft by the set-screw 25. The three clips between the fixed clip and the loose drum are loose 25 upon the shaft; but each clip is provided with a projecting lug 26. When all the pockets are located at their normal highest position, (shown by the position of pocket 3 in Fig. 1,) the lugs of all the clips engage each other and also the 30 projecting lug 27 on the loose drums, as shown in Fig. 4, so that when a downward movement is imparted to any one pocket its cables communicate a rotary movement to the loose drums in the direction of the arrow in Fig. 4, 35 which drums through the contacting clips communicate a similar rotary movement to the shaft 5, upon which the clip most remote from the loose wheel is fixed, thereby imparting a rotary movement to the fixed drums and 40 through them and the connecting-cables raising the counterbalance. It will be readily seen, however, that the loose drums connected with the other storage-pockets are not rotated, but remain stationary, because the rotary movement 45 of shaft 5 rotates the most remote clip fixed to the shaft, which causes its lug to leave the contacting lug of its neighboring loose clip until it has made almost a complete revolution about the shaft, after which its lug en-

50 gages the lug of its neighboring clip on the opposite side from that shown in Figs. 4 and 5, and the continued rotary movement of the shaft and fixed clip imparts a rotary movement to its neighboring clip; and another 55 revolution of the shaft 5 will rotate the neighboring clip until its lug has made a revolution on the shaft and engages its neighboring loose clip, and so on, until all the loose clips have been rotated, leaving the loose drums 60 stationary until the pocket has descended to its desired lowest point. The distance to which any pocket can descend without rotating the loose drums of the other pockets will depend upon the number of loose clips interposed 65 between the loose drums and the fixed clip

coating therewith, as well as the size of the loose drums. Should it be desired to increase the distance to which the storage-pocket may be moved downwardly, it is only necessary to insert another loose clip. The counterbalance when made in the form of a roll of heavy material, as lead, can be made comparatively small in diameter and extended the whole length of the storage-case or row of storage-pockets, thereby occupying a very small 75 space behind the case, the weight being effective to balance a single storage-pocket, and by means of the mechanism above described it is possible to make use of the entire weight of the counterbalance for each pocket, the 80 pockets being moved one at a time. When the lowered pocket is restored to its upper normal position, a reverse movement is communicated to the shaft 5 and the lug-clips until they are caused to resume the position 85 shown in Figs. 4 and 5, with the lugs of the several clips all in engagement with each other and with the lugs on the loose drums in their normal position, whereby another downward movement of the pocket would instantly 90 communicate a rotary movement to the shaft, so as to act upon the counterbalance. As a means for locking the other pockets in their normal position while one pocket is being moved from its normal position to a lower 95 level I provide another series of lug-clips 30 (shown in Figs. 8 and 9,) one of the outer clips 31 being provided with a hub and set-screw 32, by which this clip can be fixed upon the shaft 5, and the other end clip 33 with an arm 100 34, connected by link 35 with a lever 36, fixed upon rotary shaft 37, which runs parallel with the shaft 5 and is supported by suitable bearings in the upper part of the case-frame. Fixed upon shaft 37 by means of set-screw 105 38 is an arm 39, provided with hook 40, adapted to engage with the pocket-supporting mechanism of the remaining pockets and to hold the same securely in place when the pocket is 110 out of its normal position.

The mechanism which serves to support the pockets in their normal position consists of arms 45, one on each side of each pocket, pivoted at 46, Fig. 2, to the case-frame and provided at its oscillatory end with a right-angled 115 offset 47, having a seat 48, adapted to receive shaft 9 and support the pockets in their normal positions, as indicated by dotted lines in Fig. 2. Each pair of arms adapted to support a pocket is provided with a connecting 120 rod or shaft 49, which supports the guide-pulleys 50. When a pocket is withdrawn from its normal position, it travels in a circular path, the shaft 9 resting upon the seat 48, while the arm 45 swings from the vertical position (shown by dotted lines in Fig. 2) to approximately the horizontal position. (Shown by solid lines in the same figure.) The shaft 9 does not leave its seat 48 until the cable 7 engages the pulley 50, which then acts as a guide 125 130

for the cable, allowing the pocket to descend in a vertical line. When the pocket is in its normal position, the shaft 49 is very near the back of the case, as indicated by dotted lines 5 in Fig. 2, and the hook 40 engages with this shaft 49 when any one of the pockets is withdrawn from its normal position.

When desired, the hook-arm 39 may also be provided with a latch 41, loosely mounted 10 on shaft 37 and adapted to pass in between the shaft 49 of the pocket-support and the plate 42, secured by bolt 43 to the top of the pocket, the latch 41 being provided with a depressed seat 44, adapted to support the shaft 15 49 and prevent the pockets from accidentally being withdrawn when not positively locked in position by the hook 40. The hook-arm is provided with a lug 51, adapted to support the latch and prevent the same from dropping 20 too low when the pocket is withdrawn and at the same time leaving the hook 40 free to close down upon shaft 49 when the latch 41 is in its supporting position. (Shown by solid lines in Fig. 8.)

25 To understand fully the operation of the locking mechanism shown in Fig. 8, it should be remembered that the position of the parts shown in Fig. 8 is the position assumed when all the pockets are in their normally highest 30 position, the lug on the end clip 31, which is fixed upon shaft 5, having through the intervening lugs of the intervening clips acted upon arm 34 to raise it to the position shown in said Fig. 8, which disconnects the hook 40 from the rod 49. The pockets are sufficiently supported while all are at their normally highest position by the latch 41, held in the position shown by 35 the link 35, arm 36, shaft 37, and lug 51, fixed upon the shaft. When one of the pockets is 40 withdrawn from the latch 41 and lowered, as shown in the right-hand side of Fig. 1, a rotary movement is at once communicated to shaft 5, which moves the clip-lugs in a direction to separate the same from each other and 45 permit the arm 34 to drop, thereby permitting the hook 40 to also drop and engage the shaft 49 of all the pockets which are allowed to remain at their normally highest position and lock the same in such position, so that 50 there will be no danger of their falling out upon a person while operating a neighboring pocket, the object being to secure a positive locking device for the remaining pockets, in addition to the latches 41, while any one 55 pocket is being operated to the exclusion of the others.

The oscillatory arms 45 not only serve to support the pockets when in their normal position, but also serve to deflect the pockets and 60 their supporting-cables from the plane of its support when in its normal position to a plane wholly outside of the supporting-pivot 46, the two positions being indicated by solid and dotted lines in Fig. 2.

65 The counterbalance is intended to be of the proper weight to balance one of the storage-pockets at a time, together with its average load, and if a large part or all of the load or contents of the pocket should be removed from the pocket when in the position shown by solid 70 lines in Fig. 2—that is, at a lower level—the empty pocket would be overbalanced and forced upward unless positively locked in some position. As a means for locking the pocket in a lower level I provide a notched disk 60, 75 loose on shaft 5 and secured from turning thereon by the link 61, rigidly connecting the same with the frame of the case, as shown in Fig. 6. I also provide an arm 62, apertured to receive shaft 5, on which it is mounted, and 80 provided with the set-screw 63, adapted to fix the same to the shaft, so as to turn therewith. The arm 62 is provided with dog 64, pivoted thereon at 65 and adapted to enter the notch 66, as shown in Fig. 6, and thereby lock the 85 arm and disk relatively to each other; but the arm being fastened to the shaft 5 and the disk to the case the shaft is prevented from turning in a direction to permit the pocket to rise. As a means for unlocking this mechanism, so 90 as to permit the pocket to be raised or moved upward, the disk is provided with a projecting finger 67, up which the dog 64 rides before reaching the notches 66. To unlock the parts, it is only necessary to move the pocket 95 a little farther downward, which will move the dog 64 back to the left of finger 67, as shown in the drawings, then quickly move the pocket in the opposite direction, which will cause the dog to jump over the finger and past the notch 100 into the level surface 68, and so on past the notch, and to prevent the dog from again engaging with the notch until the pocket has been restored to its normal position a loose thin sheet-metal arm 70 is loosely mounted 105 upon shaft 5 between the disk 60 and arm 62, and the arm 62, provided with the projecting lug 71, adapted to engage the arm 70, so as to keep one just in advance of the other while going in the direction taken when the pocket is traveling upwardly. This arm 70 is so shaped on its oscillatory end as to prevent the dog 64 from engaging the notch 66, as seen in Fig. 7. When any of the pockets are pulled down from their normal position, the revolute movement of arm 62 is reversed, which causes the lug 71 to pass around shaft 5 and engage arm 70 on the side opposite to that side with which the lug is shown in engagement in Fig. 7, which forces the arm 70 away from notch 110 66, leaving it open to be engaged by dog 64. When the counterbalance and the loaded pocket are about evenly balanced, the pocket can be easily and steadily moved from a lower to a higher position; but as it approaches its 115 normal position during the later part of its movement, when it is partly supported by the oscillatory arm 45, it moves in an approximately horizontal direction, so that its weight is greatly overbalanced by the counterbal- 120

125 130

ance, and its later movements would be rapidly accelerated if some means were not provided for retarding its motion. As a means for accomplishing this result I provide a governor mechanism consisting of a bracket 80, fixed upon the case-frame by means of the screws 81 and provided with a worm-thread 83, adapted to be engaged by teeth on the toothed wheel 84, fixed upon to rotate with shaft 5, whereby rotary movements of the shaft cause a much more rapid movement of the spindle 82. To the upper end of the spindle 82 are fixed the ordinary governor balance or weights 85. The outward movement of the weights forces downwardly the sleeve 86 and causes the same to frictionally engage with the stationary surface 87 on the bearing-support, the neighboring surface of the sleeve and bearing-support being enlarged, so as to afford a considerable engaging surface. The friction of the rotating sleeve 86 on the stationary surface 87 retards the rotary movement of the worm-spindle, and consequently of the shaft 5. As a means for allowing the shaft 5 to turn in the opposite direction when the pocket is descending I make the toothed wheel 84 loose upon shaft 5 and provide means for connecting it when moving in one direction with the hub 88, fixed upon shaft 5, by means of the dogs 89, pivoted upon the hub and adapted to fly outward by centrifugal force when the shaft 5 is rapidly rotated and engage notches in the loose toothed wheel, which immediately puts in operation the governor-balls. The dogs are normally held out of engagement with the notches by means of the light coil-springs 90.

I also provide buffers to take up the shock caused by the sudden stoppage of the pockets when they reach their normal positions, which may be of any known form of construction—as, for example, an upright spring-bar 93, secured to the case-frame at its middle by the pin 94, its lower end bearing against the frame and its upper end adapted to be engaged by the guide-pulley 50.

I also provide means for assisting an upward movement of a heavily-loaded pocket consisting of a drum 100, fixed upon shaft 5 and provided with a cable 101, adapted to wind thereon and having one end secured thereto, the other end of the cable passing out through an aperture 102 in the case-wall and over the loose pulley 103, supported by ear-brackets 104, secured to the frame-case, the outer end of the cable being provided with a suitable handle 105. By pulling down upon the handle a rotary movement will be given to shaft 5, which will raise the pocket.

60 What I claim as new, and desire to secure by Letters Patent, is—

1. A plurality of movable storage-pockets in combination with a counterbalance; and means whereby the pockets can be moved up

and down, one at a time; and means for actively connecting the pockets, one at a time, with the counterbalance, substantially as described.

2. A plurality of separately-movable storage-pockets in combination with a counterbalance; operative connections, between the several pockets and the counterbalance, and means whereby the movement of any one pocket renders its connection active and all the other pocket connections inactive, substantially as described.

3. A plurality of movable storage-pockets; and means whereby the pockets can be moved one at a time; in combination with a counterbalance; operative connections between the several pockets and the counterbalance; and means for automatically inducing inaction in the several connections of all the other pockets by the movement of any one pocket, substantially as described.

4. A plurality of storage-pockets, movable, up and down, one at a time; in combination with locking mechanism at the highest level; and means whereby the movement of any one pocket from the highest level automatically locks all the other pockets at that level, substantially as described.

5. A storage-pocket movable, up and down; in combination with a supporting drum and cable; a cable-deflecting arm pivoted at its lower end to a stationary support and provided at its other end with cable-engaging mechanism for transferring the pocket from one vertical plane to another, substantially as described.

6. A storage-pocket, movable up and down; and a stationary support for the same; in combination with a supporting drum and cable; a cable-deflecting arm pivoted at its lower end to the stationary support and provided at its other end with cable-engaging mechanism for transferring the pocket from the plane of its support to a plane wholly outside of the support; and a bifurcate offset on the oscillatory end of the arm engagable with the pocket mechanism during the oscillatory movements of the arm, substantially as described.

7. A storage-pocket, movable up and down; a counterbalance and a supporting drum and cable connecting the pocket and counterbalance; in combination with an oscillatory cable-deflector, causing the pocket to travel in the arc of a circle during part of its up-and-down movements; and mechanism for automatically controlling the rate of travel during the latter part of its upward movement, substantially as described.

8. A storage-pocket, movable up and down; a counterbalance; and a supporting drum and cable connecting the pocket and counterbalance; in combination with an oscillatory cable-deflector; and a buffer adapted to be en-

- gaged by the pocket-frame at the end of its upward movement, substantially as described.
9. A storage-pocket, movable up and down; a counterbalance; and a supporting drum and cable connecting the pocket and counterbalance; in combination with mechanism adapted to be operated by hand for moving the cable in a direction to raise the pocket from one level to another, substantially as described.
10. A plurality of storage-pockets movable up and down, one at a time; a counterbalance; a drum-shaft; drums and cables for actively connecting the counterbalance with a pocket; and a hand-cable connected with the drum-shaft for raising the pocket from one level to another, substantially as described.
11. A storage-pocket movable up and down; and a counterbalance; in combination with a stop-lock adapted to close after a downward and a short, slow, upward movement to hold the pocket at a lower level and to open after a short downward and quick upward movement, substantially as described.
12. A plurality of storage-pockets movable up and down one at a time; and a counterbalance; in combination with a rotary shaft; bearings for supporting the shaft above the several pockets; one or more drums fixed upon the shaft; cable connection between the fixed drum and counterbalance; a plurality of drums loose on said shaft; cable connections between each pocket and one or more loose drums; and means for automatically rendering a loose drum active to the shaft during the down movement of the pocket supported by such drum, substantially as described.
13. A plurality of storage-pockets movable up and down one at a time; and a counterbalance; in combination with a rotary shaft; bearings for supporting the shaft above the several pockets; one or more drums fixed upon the shaft; cable connection between the fixed drum and counterbalance; a plurality of drums loose on said shaft; cable connections between each pocket and one or more loose drums; and automatically-operating mechanism for rigidly connecting with the shaft the loose drums when actively supporting a pocket, substantially as described.
14. A plurality of storage-pockets movable up and down one at a time; in combination with a weight in the form of a bar or roll; a rotary shaft supported above the pockets; fixed drums on the shaft; weight-supporting cables passed under the roll, each cable having one end secured to a stationary support and the other end to one of the fixed drums; loose drums on the shaft; cable connections between the several pockets and one or more loose drums; and means for maintaining an active connection between the shaft and the pockets one at a time, substantially as described.

In testimony whereof I have hereunto set my hand this 9th day of January, 1903.

COLLINS ARNOLD.
